UNITED STATES PATENT OFFICE.

WILLIAM JAMES DAVIDSON, OF WINNIPEG, MANITOBA, CANADA.

ASH-SIFTING SHOVEL.

1,165,574.

Specification of Letters Patent. Patented Dec. 28, 1915.

Application filed February 23, 1915. Serial No. 10,098.

To all whom it may concern:

Be it known that I, WILLIAM JAMES DAVIDSON, a citizen of the Dominion of Canada, residing at the city of Winnipeg, Province of Manitoba, Canada, have invented certain new and useful Improvements in Ash-Sifting Shovels, of which the following is a specification.

My invention relates to shovels having a screen portion and other features particularly adapting them for use in connection with the ordinary household furnace, to separate the unburned portions of the fuel from the ashes, and without setting free the usual cloud of dust incidental to this operation.

The objects of the invention are first, to provide a device of the kind described which shall have the appearance of an ordinary shovel and be handled in the same manner; second, to provide a device which may be pushed into the ashes in the furnace pit in the manner of a shovel, but which immediately thereafter becomes a sifting box having means to prevent escape of the material under treatment; third, to provide means to prevent the material in the shovel from dashing out over the top at the rear; fourth, to provide means whereby the sifting operation is assisted by contact of the sifter with the furnace. The means by which these objects are attained will be found described in the following specification, particularly pointed out in the claims, and fully illustrated in the accompanying drawings, in which:

Figure 1 is a side view of a furnace, the wall being broken away to show the interior of the ash pit, and the shovel therein in two positions. Fig. 2 is a plan view of the shovel complete. Fig. 3 is a sectional view on the line A in Fig. 2. Fig. 4 is a face view of the gate situate at the front of the shovel. Fig. 5 is a side view of Fig. 4. Fig. 6 is a front view of a slightly different style of gate. Fig. 7 is a side view of Fig. 6. Figs. 8, 9, 10 and 11 show a variety of means on the handle of the shovel by which a jar-ring contact might be made with the furnace to assist in the sifting operation.

Referring to the drawings in which similar characters of reference indicate similar

parts throughout the different views, B is the body of the shovel and C the handle. The body B is preferably made with light framework molded to shovel shape and adapted to support the sides 2 and 3, the bottom 4 and rear end 5, which are preferably all of woven wire of suitable mesh to effect the desired separation between the ashes and cinders. The lower frame members 6 and 7 may turn up at the rear to meet the upper side members 8 and 9 and be joined thereto, thence running to the center and again outward to form the outer layers 10 and 11 of the handle C, the end of which may be turned as at 12 to form a cross bar or grip.

A central frame member 13, of greater width than thickness, passes along below the bottom 4 from front to rear thereof, thence passing up the back 5 to the top thereof where it is twisted edge upward at 14 and turned to conform to the general direction of the handle C of which it forms a part 15 as the spacing member 15 between the layers 10 and 11 thereof. In the particular construction under description the member 15 is kinked upward to form the protuberances 16 and 17 on the upper side of the handle C for a purpose described hereinafter.

At the front of the shovel is a lip 18 preferably folded as shown (Fig. 3) to embrace the upper and lower surfaces of the bottom 4 and form a forward shovel edge which may be pushed into the ashes without resistance, the lip being secured to bottom and sides by rivets or other suitable means. The rear upper edge of the lip 18 may be rolled back to form the apertured members 19 adapted to interchange with the similarly formed members 20 on the gate D, a pintle passing through the members on the gate and lip to form a hinge connection therebetween. The gate D is further provided with the rearward projections 21 which operate to prevent the gate from falling down forwardly but do not prevent it from falling in the opposite direction. The shovel may also be provided with a hood E covering the upper rearward portion of the body B to prevent overflow of the material therein during the sifting operation.

The shovel is intended to be used in con-

nection with any furnace of ordinary construction having the usual ash pit below the fire grate and a door-opening thereinto. In operation the drafts of the furnace are 5 first turned on and the shovel inserted into the ash pit as shown in the position X in Fig. 1, that is to say, it is pushed under the ashes as though it were a shovel of the ordinary type, the gate D lying down on the 10 bottom of the shovel and offering no resistance to the ashes. The shovel with its load is then lifted to the position shown as Y, with the knobs 16 and 17 positioned on each side of the front plate 22 of the door 15 opening of the furnace F. The shovel is then given a sifting motion back and forth, the knobs 16 and 17 alternately coming into contact with the plate 22 of the furnace and adding a jarring effect which greatly assists 20 in the sifting. When the shovel was loaded, it will be noted that the gate D was lying down rearwardly as in Fig. 2, but at the first movement toward sifting, the ashes in 25 the shovel forced it up into the position indicated by the dotted lines D² in the different figures, which is a little past the upright, in which position it operates to prevent the material in the shovel from being thrown out over the front during sifting. 30 The hood E performs a similarly useful function at the rear. The working of the gate D it will be understood, is quite automatic, and requires no adjustment or attention.

35 It is preferable that the knobs 16 and 17 be placed upon the handle C but it is possible to place them at other points in the structure, as for instance on the sides of the body B, as indicated by the dotted lines 16^a and 17^a in Fig. 2. Also the effect of the knobs may be obtained by other means than those shown, as for instance by removing a portion of the handle as in Fig. 8, leaving the shoulders 23 and 24 to perform the functions of the knobs; or the handle may be bent as in Fig. 10 to obtain the same result.

40 Fig. 11 represents a plate 25, having the knobs 16 and 17 formed thereon and which may be secured to a handle of wood by the 45 screw nails 26 and 27.

In Fig. 9 a form of handle is shown in which only one jarring member 28 is used. This would assist the sifting to a certain extent but would not be equal in convenience 55 or effect to the double knobs previously described.

An open mesh gate D³ is shown in Figs. 6 and 7, which does not differ in function from the gate shown and described in Fig. 4, save that it adds to the sifting capacity 60 of the device and could be secured to the bottom 4 by a wire loop passed through the coils 29 at each side of the gate.

From the foregoing description it will 65 be seen that I have produced a device hav-

ing the handiness of a shovel combined with the functions of a sieve and having the other features serving to maintain the material in the sieve during treatment, with the further advantages that the sifting is 70 carried on within the ash pit of the furnace where the upward draft serves to prevent the escape of the dust necessarily created by a sifting operation.

Having thus fully described my said invention what I claim as mine is;—

1. A sifting shovel adapted to be used in the ash pit of a furnace, said shovel comprising a body having a screen portion and a handle and means adapted to engage the 80 front of the furnace to jar the shovel.

2. A sifting shovel adapted to be used in the ash pit of a furnace, said shovel having a screen portion in the body thereof, and a handle and means on the handle to engage 85 the front of the furnace to jar the shovel.

3. A sifting shovel adapted for use in the ash pit of a furnace said shovel having a screen portion and a handle and means on 90 the handle to jar the shovel, said means comprising a pair of projecting members spaced apart and positioned to alternately engage the front plate of the furnace on the opposite sides thereof as the shovel is reciprocated. 95

4. A sifting shovel adapted for use in the ash pit of a furnace, said shovel having a screen portion and a handle, projections on the handle adapted to engage the front 100 plate of the furnace and assist the sifting, and means at the mouth of the shovel adapted to allow unobstructed ingress of material to the shovel and adjustable to prevent egress of unsifted material.

5. A sifting shovel adapted for use in the ash pit of a furnace, said shovel having a screen portion, a hood, a handle and means on the handle to engage the front of the 105 furnace and jar the shovel.

6. A sifting shovel adapted for use in the ash pit of a furnace, said shovel having a screen portion, a hood, a handle, means on the handle to engage the front of the furnace and jar the shovel and means in the 110 mouth of the shovel adapted to allow ingress of material to the shovel but to prevent egress of unsifted material therefrom.

7. An ash sifter comprising a skeleton frame shaped to form a shovel having a perforate covering and a handle provided with projections on its upper side adapted to alternately engage the front of the furnace as the shovel is reciprocated in the ash pit thereof. 115

8. An ash sifter comprising a skeleton frame formed from comparatively narrow bars shaped to form a shovel having a screen fabric covering and a lip, the upper side bars of the frame being turned toward 120

each other at the back thereof, then extended rearwardly in spaced relation to each other to form a handle, and the medial bottom member of the frame being turned upwardly at the rear thereof then outwardly to occupy the space between the outer members of the handle and being provided with spaced projections thereabove adapted to engage the front of the furnace when the shovel is reciprocated in the ash pit thereof. 10 In testimony whereof, I affix my signature.

WILLIAM JAMES DAVIDSON.
